UNITED STATES PATENT OFFICE.

JOHN M. HANSEN, OF PITTSBURGH, PENNSYLVANIA.

GONDOLA CAR.

1,008,462.

Specification of Letters Patent. Patented Nov. 14, 1911.

Application filed April 27, 1910. Serial No. 558,032.

To all whom it may concern:

Be it known that I, JOHN M. HANSEN, a resident of Pittsburgh, in the county of Allegheny and State of Pennsylvania, have invented a new and useful Improvement in Gondola Cars; and I do hereby declare the following to be a full, clear, and exact description thereof.

My invention relates to freight cars, one object thereof being to provide a dump car of the general gondola type in which the door closing mechanism is exposed on the outside of the car body giving free access thereto while such mechanism is fully protected from injury such as by side contact with other cars; and another object is to provide a car having plate girder sides with such exposed pocket for the door operating mechanism.

In the most approved combined freight and dump cars the door operating mechanism has been located below the level of the car floor and generally placed under the bottom chord of the plate girder side, which was made of an angle extending inwardly from the side plate. Such construction required the separate extra angle or member, and where these cars were used for coal transportation, it left a ledge on which the coal rested and which was not always kept clean, and the angle was often eaten into by the sulfur contained in the coal. There was also the other fact that the apparatus did not give as direct or vertical a pull on the closing mechanism of the door as desirable.

The present invention overcomes these difficulties and provides a very simple car construction suitable for use in this particular type of car.

It contemplates, generally stated, a gondola car body provided with a pocket for the door operating mechanism exposed on the outside of the car side to give easy access thereto and within the side stakes or stiffeners so as to be protected thereby.

It also contemplates such a gondola car provided with a plate girder side having an inwardly extending bottom chord in the body of the side plate, in combination with side stakes or stiffeners extending across the same, so forming the exposed pocket to receive the shaft for the door operating mechanism of the car.

It also consists in certain other improvements hereinafter set forth and claimed.

In the accompanying drawing Figure 1

is a side view of the car embodying the invention; Fig. 2 is a top or plan view of a portion of the car partly broken away to illustrate the same; Fig. 3 is an enlarged cross sectional view; Figs 4 and 5 are enlarged views of different forms of door operating mechanism located within the pocket; and Figs. 6 and 7 are enlarged cross sections illustrating different constructions of car body embodying the invention.

The car embodying the invention has any suitable form of underframe, such for example as the center sills 1 and bolsters 2 and cross beams 3, and is of course provided with any suitable end wall 4. The car is provided with any suitable sides 5 and has the spaces or pockets 6 exposed on the outside of the car sides for the reception of the door operating mechanism, such pockets being within the side stakes or stiffeners 7 which thus fully protect the door operating mechanism from injury from side blows, while giving free access thereto.

In the preferred form the car is provided with plate girder sides as shown, each such side having the side plates 8 and the top chord 9 preferably formed of an angle, and the stiffeners or stakes 7 which are shown as pressed to shape. The bottom chord 10 of the car side is formed of plate metal preferably bent from the side plate 8, such chord being preferably V-shaped as illustrated, and such chord extending inwardly for a short distance. In its preferred form this bottom chord has the upper downwardly inclined portion 11 and the lower outwardly and downwardly inclined portion 12, forming the exposed pocket 6 of the car side, below which the plate is bent downwardly to form the vertical portion 13 on the same vertical plane as the main body of the side plate. The stake 7 is riveted to the side plate 8 above the pocket 6 and extends across that pocket and is riveted to the vertical base portion 13 of the side plate, being at the same time riveted to the bolster 2 or cross diaphragm 3, the rivet passing through the flange 15 thereof and also through the vertical base portion 13 of the plate and the bottom portion of the side stake as at 16. In the construction of the car where an entire metal underframe is used the lower inclined portion 12 of the side plate is also riveted to the flange 14 of the bolster or cross beam as at 17, so forming a strong connection between the underframe and the car.

sides. The car floor is preferably divided into a series of pockets 18 by means of the bolsters and cross beams, and the cross plates 19 of the underframe extend above the same and may be carried up onto the upper inclined portion 11 of the side plate and riveted thereto as at 20. In such dump cars any suitable construction of door and of door operating mechanism may be employed, the car illustrated having a metal door 21 hinged to the center sill as at 22 and provided with downwardly extending flanges, the side flanges being generally bent to vertical position as at 23, while the outer end flange 24 is bent to an incline corresponding to the downwardly inclined portion 12 of the side plate and fits closely against the same. In the pocket 6 is located a suitable door operating shaft 25 which can be mounted therein in any suitable way, such as by the brackets 26, the shaft extending for any suitable distance within the pocket. For example in the car illustrated the shaft extends through the bolster as the car has its dump doors located only between the bolsters, and in such case the pocket where it extends beyond the bolster forms a proper place for the reception of the operating mechanism for the shaft, as illustrated at 27 in Fig. 1. The shaft as thus located in the pocket 6 is fully exposed, giving easy access for adjustment of the chains, for repairs or the like, while it is within the line of the side plate and fully protected by the side stakes and therefore is not liable to injury from side swipes or the like. At the same time the downwardly inclined wall or portion 11 of the side plate provides an inclined face for the delivery of the coal or other bulk commodity directly to the opening or pocket, making that portion of the car entirely self-clearing and preventing such lodgment as would lead to rusting of the metal such as by the sulfur of the coal.

While any suitable kind of door operating mechanism may be employed I have illustrated chains for lifting the doors, these chains being connected to the operating shafts and to the outer edges of the doors and suitable openings 30, being made in the lower inclined plates 11 through which the chains can pass from the doors to the winding shaft. In this way the doors can be drawn by the chains up against the said lower inclined portion 12 of the V-shaped bottom chord and the winding shafts can be placed above the floor level and the hold on the doors as they are brought to closing position can be made much more direct. For example, as illustrated in Figs. 1 to 4, the doors are provided with suitable hooks 31 engaging with supports 32 on the car body to hold the doors closed, the hooks 31 being pivotally secured to the brackets 33 on the car doors, and the chains 35 connected to the

chain shafts 25 being secured to lugs 34 on the hooks, the shafts carrying the knockers 36 by which the hooks 31 are drawn from the connection with the lugs to permit the lowering of the doors. Such construction forms the subject matter of a separate application of even date herewith, Serial No. 558,031. In such case, as illustrated in Figs. 3 and 4, the support 32 forms part of a V-shaped casting 37 fitting into the joint between the inclined portions 11 and 12 of the pocket 6 and serves to brace or stiffen the same.

In Fig. 5 another form of car door operating mechanism is illustrated which forms the subject matter of an application of even date herewith, Serial No. 558,030, in which the chain shaft 40 has the chain 41 secured thereto and engaging with a yielding bolt 42 mounted within a spring 43, while to lock the door the bar 44 is mounted on the door on the swinging joint 45, and the shaft 40 carries the hook or cam 46 which engages with the bar 44 and so holds the door in closed position, the bar 44 as illustrated carrying a T-head 47 passing within the slot 48 and engaging the inner inclined or cam face 49 of the cam 46. In both of said figures, as will be seen, the door operating mechanism is inclosed within the pocket 6 formed by the V-shaped bottom chord of the plate girder side which gives full protection to the same while permitting easy access thereto, as above described.

In Figs. 6 and 7 I have illustrated the invention in other forms. In Fig. 6 it will be seen that the pocket is formed by bending the side plate 50 first at a downward incline as at 51, and then horizontally as at 52, and thence downwardly parallel to the main body of the plate as at 53, and riveted to the cross member 54 and stiffener 55. In this case the flat upper surface of the door 56 fits against the bottom of the horizontal portion 52 of the pocket, and the hook 57 engages with a support 58 upon said horizontal portion 52. The shaft 59 is located within the pocket, and, as is clearly shown, the draft on the chain in closing the door is directly upward. In Fig. 7 I have illustrated the pocket as formed of a separate plate extension from the side plate. In such case the side plate 60 terminates at the top of the pocket and a separate plate 61 forms the bottom chord of the plate girder side, having the downwardly inclined portion 62, the horizontal base portion 63 and the vertical portion 64 extending below the same in line with the side plate 60. The side plate 60 and the bottom chord 61 forming the pocket 65 are riveted to the stakes 66 and the bottom portion 64 of the chord plate is riveted to the base of the stiffener and also to the flange of the bolster or cross beam 67. These figures are further illustrative of

the invention as to the different forms which it may take, the shape of the pocket and the manner of constructing the same being varied as found desirable, but in any form having the advantage of protecting the operating mechanism from direct contact with the load and yet giving free access to the same for adjustment or repair, while such mechanism is fully protected from injury by side blows on the car by means of the stakes or stiffeners of the car side.

In the car, as so constructed, I am thus enabled by providing the plate girder side with the V-shaped chord bent in the body 5 of the side plate or riveted thereto and forming practically part thereof, to form the bottom chord member of the side plate girder side, and in addition to providing the pocket for the reception of the door operating mechanism, I provide a bottom chord of great strength through the walls 10 and 11 and the stakes 8 extending across the pocket, largely increasing the stiffness of the car body and its power to sustain load. I 15 also am enabled in cars of this particular type to carry the actual union or joint between the car sides and the cross members, such as the bolsters 2 and cross bearers 3, down to the bottom of said cross members,

forming a much stronger connection than 30 where an ordinary angle is used for the base chord of the plate girder side, while giving all the advantages above referred to and providing the exposed pocket for the operating shaft.

What I claim is:

1. In a car, the combination of an under-frame having cross members and a plate girder side having a V-shaped bottom chord extending inwardly from the side plate and having a lower inclined portion riveted to a like inclined flange on said cross members.

2. In a car, the combination of an under-frame having cross members, and a plate girder side having a V-shaped bottom chord 45 and a vertical portion below said chord, the lower portion of said chord being inclined, the cross member having an inclined flange riveted to the lower inclined portion of said chord and a vertical flange riveted to the 50 said vertical portion below the chord and to the stiffening members of the plate girder.

In testimony whereof, I the said JOHN M. HANSEN have hereunto set my hand.

JOHN M. HANSEN.
